UNITED STATES PATENT OFFICE.

EDWARD GOODRICH ACHESON, OF NEW YORK, N. Y., ASSIGNOR TO ACHESON CORPORATION, OF NEW YORK, N. Y., A CORPORATION OF DELAWARE.

METHOD OF DEFLOCCULATING SOLID MATERIALS.

1,223,350.

Specification of Letters Patent.

Patented Apr. 24, 1917.

Application filed January 17, 1917. Serial No. 142,861.

To all whom it may concern:

Be it known that I, EDWARD GOODRICH ACHESON, a citizen of the United States, residing at New York, in the county of New York, and State of New York, have invented certain new and useful Improvements in Methods of Deflocculating Solid Materials, of which the following is a specification.

This invention relates to methods of deflocculating solid materials, such as graphite, lampblack, amorphous pigments or the like.

It is now well understood in the art that such materials, when rubbed, ground, or subjected to a process of attrition in presence

of so-called "deflocculating agents" are ultimately reduced to a state of extreme subdivision, as a result of which a greater or less proportion of the particles become permanently suspensible in water and capable of diffusing therethrough, and may by appropriate treatment be transferred to and suspended in vehicles other than water, for example mineral oils, etc. The deflocculating agents above referred to comprise tannin and tannin-like substances, and other organic bodies or products having similar effects. Certain methods of deflocculating amorphous bodies and utilizing the deflocculated product are disclosed in my prior United States Patents Nos. 722,791; 843,426; 844,989; 875,881; 895,063; 911,358; 931,832; 964,478; 966,636; 986,793; 1,030,372; 1,082,386; 1,201,994.

According to the present invention, the deflocculation of amorphous bodies is accomplished by a novel method, the essential feature of said method being that the amorphous substance, mixed with the deflocculating agent or an aqueous solution thereof, is subjected to a number of distinct and separate rubbing operations during which the particles of the mass are subjected to attrition, with intermediate periods which may be defined as periods of relative rest, in the sense that during such intermediate periods the individual particles of the charge are not subjected to an active or intensive attrition or rubbing.

The invention may be carried out in apparatus of various types, and may be operated either according to the so-called "batch" system, or continuously or semi-continuously in the sense that the charge is introduced into the mill and is discharged therefrom either continuously or from time to time.

Certain types of apparatus which may be used for carrying the invention into effect are diagrammatically illustrated in the accompanying drawings.

Referring to said drawings,—

Figure 1 represents in vertical section a simple form of mill capable of being operated in accordance with the invention;

Fig. 2 is a similar view of a modified form of mill capable of continuous operation; and

Fig. 3 is a similar view of a further modification, the mill being of the vertical type capable of continuous operation.

Referring to Fig. 1, 1 represents a driven roll, which may be of iron or steel covered externally with canvas or other suitable fabric 2. This roll is mounted parallel to but out of actual contact with the base plate 3, a suitable clearance, (say one-sixteenth to one-eighth inch or somewhat more) being provided between the roll and the plate. The roll is preferably mounted in a hopper-like receptacle indicated at 4, is carried upon a shaft 5 extending through the end walls of the hopper, and is arranged to be driven by application of any suitable power at moderate speeds, say ten to sixty revolutions per minute. The roll and its mounting should be sufficiently rigid to withstand the heavy pressures involved in the operation. In practice the graphite or other material to be deflocculated is mixed with the proper proportion of the deflocculating agent in aqueous or ammoniacal solution, the mixture forming a stiff paste of the character disclosed in my prior patents above referred to.

In the case of graphite a suitable paste will contain approximately 34 to 38 per cent. of total moisture. This paste, indicated at 6, is charged into the hopper at one side of the roll, and by the revolution of the latter in the proper direction is transferred beneath the roll to the other side of the hopper. After a suitable time interval the direction of rotation of the roll is reversed, and the material is again transferred beneath the same, this operation being repeated as often as may be required to secure the desired degree or percentage of deflocculation. For example, it was found in one specific instance that 60 passages of the charge beneath the roll, a four-minute interval being permitted between the completion of one passage and the beginning of the next, sufficed to deflocculate approximately five per cent.

of the graphite in the charge. The deflocculated material may if desired be removed in aqueous suspension, and the residue re-treated, as fully explained in the prior patent above mentioned; or for certain applications such separation may be omitted. A fixed scraping blade 7 may be used in case of necessity to remove the paste from the roll, although in case of a properly prepared paste this is usually unnecessary.

Fig. 2 illustrates a modification of the device which is adapted for continuous operation by the provision of a plurality of attrition rolls arranged in series in the path of the material. In this figure the casing comprises plane upper and lower walls 8 and 9, and carries a plurality of canvas-covered rolls 1, four of these being illustrated, the rolls being preferably so mounted as to provide a slight clearance from the lower plate 9 but a wiping contact with the upper plate 8. 10 represents the charging hopper. The rolls driven by suitable gearing (not shown) in the direction indicated by the arrows, sub-ject the charge to a series of rubbings or periods of intense attrition, alternating with periods of relative rest during which the charge remains between the rolls. By adjusting the spacing between the rolls the period of relative rest may of course be varied as desired. By mounting the rolls in wiping contact with the upper casing plate any tendency of the paste to follow the rolls toward the charging end of the mill is easily overcome.

A further modification of a vertical type is illustrated in Fig. 3. In this figure the casing is constructed with plane sides 11, with which the two sets of rolls, 1 and 1^a, are mounted in wiping contact and in superposed series. Inasmuch as the attrition occurs in this case between two moving surfaces, instead of between a moving and a stationary surface as in the constructions previously described, it is desirable that the two sets of rolls should be driven at differing peripheral speeds in order to intensify the rubbing action. For example, the rolls 1 may be driven at about 15-20 revolutions per minute, and the rolls 1^a at a somewhat higher rate, say 20-30 revolutions per minute, these figures being given however merely

by way of example. In this construction it is preferred to provide above each set of rolls, except the uppermost or feeding rolls, 55 a grid which may comprise a number of stiff iron rods 12, say three-eighths inch in diameter and lying parallel to each other at two to three inch intervals, said rods extending between the side plates of removable iron frames 13, which in turn rest upon angle-bars or equivalent supports 14. The purpose of these grids is to retain the paste in the spaces intermediate the rolls for the time required for securing the best results, 65 which time will of course vary somewhat according to the nature of the material treated, the character of the deflocculating agent and perhaps other factors. Obviously, other means or arrangements having a like func- 70 tion may be substituted for the grids.

Without thereby limiting my invention, it may be suggested as a possible explanation of the observed effects, that the periods of relative rest which alternate with the periods 75 of intense attrition may be necessary to afford time for a certain penetration of the deflocculating agent into the substance of the minute masses which are to be deflocculated, the surface portions of these minute 80 masses being rubbed off or removed during the ensuing period of attrition. Whatever the explanation may be, the fact has been clearly demonstrated that the deflocculation proceeds most rapidly when the operation 85 is subdivided as described above into more or less definite and distinct periods of attrition and relative rest, irrespective of the means employed for accomplishing such subdivision of the operation. 90

I claim:—

A method of deflocculating solid materials, consisting in subjecting said materials, mixed with a deflocculating agent and in paste form, to alternate periods of 95 attrition and relative rest, until the desired percentage of deflocculation is attained.

In testimony whereof I affix my signature in presence of two witnesses.

EDWARD GOODRICH ACHESON.
